SASH BALANCE

Dawson J. Dinsmore, Sioux Falls, S. Dak.

Application February 24, 1948, Serial No. 10,425

2 Claims. (Cl. 16—198)

1

This invention relates to sash balances of spring type and more particularly to those of the kind that are placed overhead and located on the lintel or head jamb of the framing of a window opening instead of the side jamb thereof, so as to thus permit simplification and the making more compact of the upright side portions of the framing and without necessitating any material change in the size or a departure from the form and arrangement of the lintel or head jamb.

An object of the invention is to produce a spring type of balance which is usable for both the upper and the lower sashes of windows, is simplified and made comparatively small and compact in size, yet highly efficient and effective in use, is manufactured at a minimum cost and can accordingly be marketed and sold at a low price, and is easily installed for use.

Generally stated, the invention consists primarily in a comparatively short yet appreciably elongated and relatively narrow, rigid body member which is of a definite though minimum length and mountable horizontally and supportedly on the lintel or head jamb of a window frame, said body member resting throughout the greater extent thereof on the lintel or head jamb and being there fastened at its inner end only and having its outer end portion extended so as to overhang or project into the vertical runway provided in the side jamb of the window frame so as to receive the window sash slidably fitted therein. This body member, which is preferably of an open-topped channel form throughout its length, contains a peculiarly formed and operated, longitudinally movable, spring-retracted carriage having a retainer portion working in slidably engageable relation to the spring element whereby the carriage is retained in the body, there being a flexible sash-supporting element such as a strong cord or wire which is attached to the carriage in opposition, to the spring element and is looped and relooped several times compoundedly about a series of rollers journaled on the carriage and an opposed series of rollers journaled in fixed position on the body member so that a maximum outplay of the flexible cord or wire element between the sash and the set of rollers on the balance body causes only a slight travel of the carriage and stretching of the spring element.

An illustrative but non-limiting embodiment of the invention is shown in the accompanying drawings, wherein:

Figure 1 is a fragmentary top plan view of a

window frame in which a pair of sash-balances are shown as placed on the lintel or head jamb of the frame;

Figure 2 is a fragmentary elevational view and section taken substantially on the line 2—2 of Figure 1;

Figure 3 is a fragmentary end view of the upper portion of a window frame showing a pair of sash-balances placed thereon as in Figure 1, one for the upper and one for the lower sash;

Figure 4 is an enlarged cross-sectional view taken on or about the line 4—4 of Figure 1 through the channelled body member, the carriage and the pairs of spring elements;

Figure 5 is a cross-section taken on the line 5—5 of Figure 1 through the channelled body member adjacent the set of stationarily located rollers for the flexible cord or wire; and

Figure 6 is a perspective view of the carriage element detached.

Referring now to the drawings in detail, the numeral 10 designates, as a whole, a window frame having a lintel or head jamb 11 at the top thereof, on which is placed a pair of sash-balances, each designated generally by the numeral 12, there being one for the upper sash 13 and one for the lower sash 14. The upper sash 13 has its side edges fitted slidably in the usual vertical channel or runway 15 provided in the side jambs of the window frame 10, and the lower sash 14 is likewise fitted in similar channels or runways 16 in the framing.

The window frame and sash constructions, in themselves not a part of the present invention, may be of any ordinary or approved form and arrangement. Hence, the same are not shown in full detail but only sufficiently to illustrate a practical application of the present invention thereto.

The invention resides principally in the novel construction and arrangement of the balance itself and the particular way in which it is mounted and operates in use, and the same will now be described in detail.

As shown, the device comprises an elongated and relatively narrow channelled body member of a definite though minimum length, having a flat bottom 17 and straight right-angular side walls 18, 19. This member, as shown, is open at its top throughout its length and at its opposite ends, and when installed for use it is placed so as to rest flatwise on top of the horizontal lintel or head jamb 11 of the window frame or upon a specially cut or otherwise provided seat portion formed in said frame part. In any case, this

body member is set and supported horizontally overhead in working position. So, too, its outer end portion 20 is projected so as to enter or overhang the upper part of the vertical runway in the side jamb of the window frame in which the upper or the lower sash, as the case may be, is slidably fitted.

In use, there may be provided only one of the balances of the present invention for each sash, in some cases, or two balances (one at each side of the sash) in other cases, depending upon the weight of the sash itself and the sustaining strength of the spring element provided in the balance. However, for the average smaller and lighter weight sashes, only one of the balances will be ordinarily used, but, for larger and heavier sashes two balances may be necessarily used, one at each side of the sash.

It is here noted that in cases where only one balance is used for each sash, particularly when there is an upper and a lower sash in the same window frame, a pair of the balances may be placed side by side on the lintel or head jamb and at one side of the frame, or, if desired, the balance for the upper sash may be placed at one side of the frame and that for the lower sash at the opposite side of the frame.

Obviously, the balance of the present invention can be used for sustaining sashes in the conventional style of window frame having its side jambs prepared for accommodation of the regular weighted sash cord hanging of the sash. However, if designed especially for use of the balance of the present invention, simplification and compactness of side jamb structure of the window frame is possible because the chamber or space for accommodation of sash cord weights can be eliminated and the side jamb provided with only the runway or runways for the sliding sash or sashes.

The forward end portion of the bottom 17 of the elongated channelled body 12 of the balance which enters or overhangs the vertical runway 15 or 16 of the side jamb of the window frame, is provided with an opening 21 (see Figures 1 and 2) which may be of any desirable form, but, as shown, is a circular aperture. Through this opening 21 a flexible cord or wire 22 is passed downwardly from a spring-influenced winding and take-up means on the body 12 to be presently described more fully in detail. said cord or wire 22 being attached at its end to the upper or lower sash, 13 or 14, as the case may be. The attachment of the cord or wire 22 to the sash may be effected in any approved manner, but, preferably, detachably as indicated in Figures 2 and 3, wherein the cord or wire 22 is provided with an apertured clip 23 to releasably engage securely over a hook element 24 provided on the sash 13 or 14.

The weight of the sash transmitted through the cord or wire 22 to the balance body 12 holds the latter against the lintel or head jamb 11, said body 12 resting firmly and supportedly throughout the major portion of its length on the lintel or head jamb. This makes for stability and dependability of support for the balance, but, to assure positive placement of the balance, it is held from lengthwise as well as upward lifting and tilting movement by providing an apertured extension 25 of the bottom 17 of the body 12 at its inner end and fastening the same as by a screw 26 or otherwise to the lintel or head jamb 11.

As shown (for clarity see Figures 1 and 2 in particular) the channelled body 12 is provided on

its side wall 19, near the forward end thereof, with a series of three rollers 27. These rollers, which, as shown, are concave or grooved peripherally, are journalled in fixed position between a short, supplemental, longitudinal partition plate 28 and the adjacent portion of the side wall 19. This plate 28 may be an integral wall extension of the bottom 17 of the body 12, or, if it is in the form of a separate rectangular plate and is made to rest at its bottom edge solidly on the bottom 17 and the spindles on which the rollers 27 rotate are firmly riveted in the plate 28 and the wall 19, then ample rigidity is afforded the mounting of the rollers 27 to withstand strains imposed thereon by the pulled cord or wire 22 which is looped and relooped around said rollers and a similar set of rollers 30 that are journalled on a carriage 31 to be now described in detail.

The carriage, designated generally by the numeral 31, comprises a main body plate 32 of a definite length which is considerably shorter than the balance body member 12. At its forward end this plate 32 is provided with a pair of upper and lower hooks 33, punched and struck from the plate and to which the forward ends of a parallel pair of helical springs 34 are attached, as at 35. Said springs extend rearwardly and are housed between the wall 18 of the balance body 12 and said carriage plate 32.

The rear ends of the springs 34 are fastened, as at 36, to hook members 37 provided on the adjacent inner face portion of the wall 18 of the balance body 12. As shown, these springs 34 extend in parallel, slightly spaced apart relation to each other and at all times are stretched to some extent and under tension. Hence, they afford an effective guiding provision for a lateral lug or flange formation 38 at the rear end of said plate member 32 of the carriage 31.

With the lateral lug or flange 38 of the carriage 31 projected between the parallel pair of upper and lower springs 34, if two of the springs are provided as shown, or under a single spring if such be provided in the same location as the upper one of the pair shown, said upper spring or the single spring, as the case may be, serves to prevent undue lifting of the carriage 31 from the bottom 17 of the channelled body member 12 of the balance, yet the carriage is freely movable longitudinally close to said bottom 17 of the body member. So, too, the spring elements 34 are free for stretch and contraction thereof.

It is here noted that spring element 34, in either single or dual number as provided, is obviously of ample strength to hold the window sash at any position to which it is moved up or down and at the same time serves as a counterbalance to enable the raising of the sash with slight effort on the part of the operator and permits lowering of the sash safely and without self-dropping movement.

As hereinabove noted, the carriage has a set of rollers 30, similar to the before described rollers 27, journalled thereon, one end of each spindle 39, for said rollers 30 being riveted firmly in the main plate 32 of the carriage and opposite ends of the spindles 39 being likewise secured in a short supplemental plate 40.

All of the rollers 27 and 30 may be of the same size, but, preferably, those of each set, either stationarily mounted on the forward portion of the body member 12 or on the rear portion of the carriage 31, are in sequentially different sizes graduating from largest diameter of the outermost one of each set to smallest diameter of the innermost one of each set. This is to facilitate looping and

relooping the cord or wire 22 in a compound relation about the rollers 27 and 30, with one end of the cord or wire attached to the sash as hereinbefore stated and indicated at 23, 24, and the other end of the cord or wire 22 fastened, as at 41, to the bottom 17 of the channelled body member 12 (see Figures 1, 2 and 5). With this varied diameter provision of the rollers 27 and 30, the looped and relooped portions of the cord or wire are movable about the rollers 27 and 30 without interference of one looping with the others.

The compound looping and relooping of the cord or wire 22 is illustrated in Figures 1 and 2. As shown, the cord or wire, starting from the end that is fastened, as at 41 to the bottom 17 of the channelled body member 12, is carried rearward under and up over the smallest roller 30 on the carriage 31, thence forward over the smallest stationary roller 27 on the body member and down under the same. It is then carried rearward under and around the middle larger roller 30, thence again forwardly, over and down under the middle stationary roller 27, whence it is again carried rearward, under and up over the largest and outermost carriage roller 30, and then forwardly and down over the outermost and largest stationary roller, from which latter the cord or wire 22 is carried downward and attached, as at 23, 24, to the sash 13 or 14, as the case may be. With this particular looping and relooping of the cord or wire 22, and one of its ends attached, as at 41 to the body member 12, with its opposite end attached, as at 23, 24, to the sash 13 or 14, as the case may be, downward movement of the sash pulls the cord or wire 22, thereby drawing the carriage forwardly and stretching the spring element or elements 34 in either a single or multiple provision thereof, whereas, if the sash is lifted, the spring element or elements as the case may be react to pull the carriage rearwardly and thus the cord or wire 22 between the sash place of attachment and the inner end which is attached to the body member 12 is kept taut constantly.

It is clearly evident that with the provision of the compound looping and relooping of the present invention, the cord or wire 22 can be extended a considerable distance as the sash moves downwardly yet the carriage 31 travels at the same time a distance forwardly only a small fraction of the downward travel of the sash. So, too, it is apparent that while the stretch of the spring element 34 is comparatively slight, like the travel of the carriage 31, the spring is always taut under tension and comparatively stiff transversely thereof between its ends. Hence, with the lateral lug or flange 38 of the carriage 31 projected under the spring 34, as hereinbefore described, the carriage is held close to the face of the bottom 17 of the channelled body 12 yet it is free to move easily forward under pull of the sash cord or wire 22 and rearwardly under reaction of the spring element. This is an important and advantageous feature of the present invention.

While the shown number of three rollers 27 and 30 in the two sets as provided in the construction and arrangement illustrated in the drawings is ideal for use with the average size of window sash and length of extension travel required of the sash-cord or wire and in keeping the length of the body member 12 within the desired practical dimension for the purpose intended, it is obvious that the number of rollers may be increased or decreased in some adaptations of the invention.

A particular advantage in the construction and arrangement of the balance of the present in-

vention, in addition to the utilitarian features hereinbefore pointed out, is in the particular way in which the ends of the spring elements 34 are respectively detachably fastened to the rear portion of the wall 18 of the body member 12 and to the forward portion of the carriage plate 32. A further advantage is that the spring elements 34 are housed and well protected between the wall 18 of the body member 12 and the plate 32 of the carriage 31 as shown. A still further advantage is that all of the cooperative working parts of the balance are contained and protected as a complete unit within the channelled body member 12.

Obviously, structural changes are possible within the spirit of the invention as defined in the appended claims. Therefore, the invention is not limited to the specific construction and arrangement shown in the accompanying drawings.

In this specification the cord or wire 22 must be of flexible material and therefore in the claims will be referred to as a flexible connector.

What is claimed is:

1. An overhead spring-influenced sash balance, the same comprising a horizontal body member, elongated and relatively narrow but of a definitely minimized length and installed for use supported lengthwise on the lintel or head jamb of a window frame, with its forward end portion projected to overhang in the upper part of the vertical sash-runway formed in the side jamb of the frame, said body member having a series of rollers journaled, as a distinct set, stationary on the forward portion thereof, and at least one roller of the set being positioned in alignment with the sash-runway, a carriage mounted rearwardly of said set of rollers, longitudinally movable within said body member and having a similar set of rollers journaled thereon in opposed cooperative relation to said first-mentioned set, the roller of each set of rollers being of different diameters, the one of greatest diameter being adjacent the forward end of the body member and positioned over the sash-runway of the window frame, the rollers of the same set decreasing in diameter rearwardly, the set of rollers carried on the carriage being reversely graduated in diameter, with the one of least diameter foremost and that of greatest diameter rearmost, spring means placed under constant tension on the body member to normally urge the carriage in a rearward direction and away from said first-mentioned set of rollers, and a flexible connector attached to a sash fitted slidably in the window frame, said flexible connector being extended from the sash upwardly, thence supportedly over the roller of the stationary set which is positioned within the sash-runway of the frame, whence it is looped and re-looped compoundedly back and forth in succession on about the stationary set of rollers on the body member and the set journaled on said carriage and finally fastened at its inner end to the body member, whereby, a forced lowering of the sash causes a pull on the flexible connector and a travel of the latter from the supporting roller of the stationary first-mentioned set a distance correspondingly equal to the travel of the sash, and, due to the compound loopings of the flexible connector between the stationary set of rollers and the set on the said carriage, causes a fractional distance movement of the carriage forwardly on the body member, with a corresponding stretching of the spring means, and upon a lifting of

the sash; the spring means reacts to move the carriage rearwardly.

2. An overhead spring-influenced sash balance, the same comprising a horizontal body member, elongated and relatively narrow but of a definitely minimized length, and installed, for use, supportedly lengthwise on the lintel or head jamb of a window frame, with its forward end portion projected to overhang in the upper part of the vertical sash-runway formed in the side jamb of the frame, said body member having a series of rollers journaled, as a distinct set, stationarily on the forward portion thereof, and at least one roller of the set being positioned in alignment with the sash-runway, a carriage mounted rearwardly of said set of rollers, said carriage having a projection in the form of a flange, extending laterally, said carriage being longitudinally movable within said body member and having a similar set of rollers journaled thereon in opposed cooperative relation to said first-mentioned set, the roller of each set of rollers being of different diameters, the one of greatest diameter being adjacent the forward end of the body member and positioned over the sash-runway of the window frame, the rollers of the same set decreasing in diameter rearwardly, the set of rollers carried on the carriage being reversely graduated in diameter, with the one of least diameter foremost and that of greatest diameter rearmost, spring means comprising a plurality of parallel spaced apart helical springs placed under constant tension on the body member to normally urge the carriage in a rearward direction and away from said first-mentioned set of rollers, said spring means

35

25

30

35

acting as a guide for the lug on said carriage, and a flexible connector attached to a sash fitted slidably in the window frame, said flexible connector being extended from the sash upwardly, thence supportedly over the roller of the stationary set which is positioned within the sash-runway of the frame, whence it is looped and re-looped compoundedly back and forth in succession on about the stationary set of rollers on the body member and the set journaled on said carriage and finally fastened at its inner end to the body member, whereby, a forced lowering of the sash causes a pull on the flexible connector and a travel of the latter from the supporting roller of the stationary first-mentioned set a distance correspondingly equal to the travel of the sash, end, due to the compound loopings of the flexible connector between the stationary set of rollers and the set on the said carriage, causes a fractional distance movement of the carriage forwardly on the body member, with a corresponding stretching of the spring means, and upon a lifting of the sash the spring means reacts to move the carriage rearwardly.
